SPECIMEN RECEPTACLE

Marion E. Terlizzi, Huntington, W. Va., assignor
of forty-five per cent to George Billy, McKees-
port, Pa.

Application November 21, 1949, Serial No. 128,625

3 Claims. (Cl. 4—141)

1

This invention pertains to a receptacle and means for retaining the same in a commode for receiving specimens of urine or other excrements of the body.

The primary object of this invention is to collect specimens of materials excreted by the body in a convenient and hygienic manner.

Another important object of this invention is to provide a device of this character which may be easily applied to conventional commodes of varying size and in selected relative position thereto.

Another object of this invention is to provide a device of this character from which collected specimens may be easily dispensed into test tubes or the like, and which will be discribable for cleaning and sterilization.

A meritorious feature of the present invention resides in the provision of an extensible support member for the receptacle which will permit the same to be used with commodes of varying size.

Another important feature of the present invention resides in the pivotal connection between the support arms which make up the support member, which, together with the extensible nature of the support member, permits the receptacle to be positioned as desired in a commode.

A final feature to be specifically enumerated herein resides in the novel means provided for locking the arms in adjusted position and securing the receptacle to the arms.

These, together with various ancillary features and objects of the invention which will later become apparent as the following description proceeds, are attained by the present invention, a preferred embodiment of which has been illustrated by way of example only in the accompanying drawings, wherein:

Figure 1 is a perspective view of the present invention showing the same applied to a conventional commode which is indicated in dotted outline;

Figure 2 is a side elevational view of the specimen collector; and

Figure 3 is an enlarged vertical sectional detail view, being taken substantially upon the plane of the section line 3—3 of Figure 2.

Reference is now made more specifically to the accompanying drawings wherein like numerals designate similar parts throughout the various views, and in which a conventional commode is indicated generally by the numeral 10, which, it will be understood, customarily includes side walls 12 and a hinged seat 14.

2

The specimen collector, indicated generally by the numeral 16, includes a receptacle 18 which is secured to an extensible support member comprising a pair of arms 20 and 22. As best shown in Figure 3, the inner end of the arm 20 is bifurcated to provide spaced extensions 24 between which the inner end of the arm 22 is slidably and telescopically received. The extensions 24 and the arm 22 are provided with registering longitudinal slots 26 and 28, respectively, which receive a threaded rod or stud 30 that is suitably secured to the under side of the receptacle 18 and depends therefrom. The rod 30 is provided with washers 32 on opposite sides of the extension 24 and is provided with a wing nut 34 at its lower end.

As thus far described, it will be readily apparent that the arms 20 and 22 are separately extensible from the receptacle 18 with the bolt 30 riding in the slots provided therein, and that the arms are each pivotally connected to the receptacle 18 with the rod 30 acting as a pivot. It will therefore be clear that the arms 20 and 22 may be rotatably and extensibly adjusted relative to the receptacle 18 and locked in the adjusted positions by tightening the wing nut 34.

As shown in Figure 2, the arms 20 and 22 are bent upwardly and outwardly adjacent their inner ends, thence outwardly and are provided with downturned ends 38 for a purpose to be presently set forth.

It is believed that the operation of the device will be readily understood. The arms 20 and 22 are rotatably and extensibly adjusted and locked in the adjusted position relative to the receptacle 18 by means of the wing nut 34 so that the receptacle 18 will be disposed within the commode 10 at the desired position with the arms 20 and 22 resting upon the side walls 12 with the downturned portions or hooks 38 engaging the side edges of the side walls 12. The hinged seat 14 is then swung down upon the side walls 12 and the device is ready for use.

It will be readily seen that the legs 20 and 22 are bent as previously described to position the receptacle 18 below the hinged seat 14.

It is within the contemplated scope of this invention that the adjusting means shown in Figure 3 could be dispensed with and spring means substituted in lieu thereof for biasing the arms 20 and 22 toward each other for engaging the hooks 38 with the side walls 12, in which event the device would be self-adjusting.

In the preferred construction, the receptacle

18 and the arms 20 and 22 are formed of non-corrodible material such as stainless steel. The receptacle 18 is preferably provided with a lip 40 whereby the contents thereof may be conveniently dispensed into a test tube or the like.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. For use with a commode having side walls, a specimen collector comprising a receptacle, an externally threaded stud depending from the receptacle, a pair of oppositely extending arms having overlapping adjacent portions, registering openings through said portions, said stud extending through the openings, and a nut threaded on the stud securing the arms to the receptacle, said arms being angularly adjustable about the stud as a pivot when the nut is loosened and adapted to engage the side walls of a commode and to support the receptacle therebetween.

2. For use with a commode having side walls, a specimen collector comprising a receptacle, an externally threaded stud depending from the receptacle, a pair of oppositely extending sup-

port arms having overlapping adjacent end portions, said portions having registering elongated slots, said stud slidably extending through the slots, and a nut threaded on the stud securing the arms in adjusted relation to the receptacle, said arms being adapted to engage the side walls of a commode and support said receptacle thereon.

3. For use with a commode having side walls, a specimen collector comprising a receptacle, a first arm having a bifurcated end portion and a second arm having an end portion slidably received within the bifurcated end portion, said portions having registering elongated slots, a fastener slidably received in said slots and securing the arms in adjusted relation, said receptacle being disposed above said portions, and means securing the receptacle to the fastener, the ends of the arms remote from said portions being adapted to engage and rest upon the upper edges of the commode side walls to support the receptacle.
